UNITED STATES PATENT OFFICE.

HENRY A. WALTON, OF FORT SCOTT, KANSAS.

DESIGN FOR A DISTRIBUTER OF DEODORIZERS AND DISINFECTANTS.

49,681.

Specification for Design.

Patented Sept. 19, 1916.

Application filed July 7, 1916. Serial No. 108,076. Term of patent 7 years.

To all whom it may concern:

Be it known that I, HENRY A. WALTON, a citizen of the United States, and a resident of Fort Scott, in the county of Bourbon and State of Kansas, have invented a new, original, and ornamental Design for a Distributer of Deodorizers and Disinfectants, of which the following is a specification, reference being had to the accompanying drawing, forming part thereof.

The figure is a view in perspective of the distributer showing it attached to an electric fan with which it operated.

I claim:

The ornamental design for a distributer of deodorizers and disinfectants, as shown.

HENRY A. WALTON.
